US00D793390S

(12) **United States Design Patent** (10) Patent No.: **US D793,390 S**
(45) Date of Patent: ** Aug. 1, 2017

(54) **HEAD MOUNT UNIT FOR VIRTUAL REALITY SYSTEM**

(71) Applicant: **Wen-Tse Huang**, Kaohsiung (TW)

(72) Inventor: **Wen-Tse Huang**, Kaohsiung (TW)

(**) Term: **15 Years**

(21) Appl. No.: **29/567,190**

(22) Filed: **Jun. 7, 2016**

(51) LOC (10) Cl. **14-02**

(52) U.S. Cl.

USPC **D14/372**

(57) **CLAIM**

We claim the ornamental design for the head mount unit for virtual reality system, as shown.

DESCRIPTION

FIG. 1 is a front perspective view of a head mount unit for virtual reality system showing my design;

FIG. 2 is a rear perspective view of the head mount unit for virtual reality system shown in FIG. 1;

FIG. 3 is a front elevational view of the head mount unit for virtual reality system shown in FIG. 1;

FIG. 4 is a rear elevational view of the head mount unit for virtual reality system shown in FIG. 1;

FIG. 5 is a left elevational view of the head mount unit for virtual reality system shown in FIG. 1, the right elevational view being a mirror image of the left elevational view;

FIG. 6 is a top plan view of the head mount unit for virtual reality system shown in FIG. 1; and,

FIG. 7 is a bottom plan view of the head mount unit for virtual reality system shown in FIG. 1.
